UNITED STATES PATENT OFFICE.

LYMAN B. LANGWORTHY, OF CHICAGO, ILLINOIS.

ART OF SHEET PILING.

Application filed August 4, 1923. Serial No. 655,627.

This invention relates to improvements in the art of sheet-piling such as is frequently used in forming the sides of coffer-dams, dikes, bulkheads, earth or water retaining walls, and the like. By the use of my invention, strong, durable sheet-piling may be quickly and cheaply constructed which, when completed, forms practically a continuous wall impervious to water. Other features and advantages, and the details of my invention will be fully understood by referring to the following specification and accompanying drawings.

In that form of device embodying the features of my invention, shown in the accompanying drawings,

Figure 1 is a view in side elevation of a section of sheet-piling showing my improved bonding gun in place,

Figure 2 is a view taken as indicated by the line 2 of Figure 1,

Figure 3 is a view in top elevation of one of the piles showing the barrel of the gun in cross section,

Figure 4 is a vertical sectional view on an enlarged scale of the hopper of the gun,

Figure 5 is a vertical sectional view on a still larger scale showing details of the gate, gate mechanism, and associated parts at the bottom of the hopper,

Figure 6 is a view in front elevation of one of the hooks used to fasten the hopper to the barrel of the gun,

Figure 7 is a view taken as indicated by the line 7 of Figure 6,

Figure 8 is a view taken by the line 8 of Figure 5,

Figure 9 is a view taken as indicated by the line 9 of Figure 5,

Figure 10 is a view taken as indicated by the line 10 of Figure 5, and

Figure 11 is a vertical sectional view of the lower end of the barrel of the bonding gun showing the removable cap in place.

As shown in the drawings, 20, 20 indicate piles which are here shown as made of concrete and provided with longitudinal holes 21 to accommodate jets which may be used to assist in placing the piles to form the sheeting. Each of the piles 20 is provided at one edge with a groove 22, and at its other edge with a ridge 23 provided with a concave groove 24. As shown, the ridge 23 is adapted to fit into the groove of an adjacent pile when the sheeting is formed so that there will be left between each two

adjacent piles, a channel 25 circular in cross section.

After the piles are in place, the channel 25 and any cracks that there may be between the edges of the piles, as indicated by 26, are grouted in the following manner to bond the piles together. I provide a bonding gun which comprises, in general, a hopper 27 adapted to contain a charge of grout 60 and a cylindrical barrel 28 for conducting the grout from the hopper into the channel 65 25.

The gun may be supported in any convenient manner so that it may be moved into 70 various positions for use, and any convenient means may be provided for raising and lowering the same. I have here shown the supporting means as including a boom 29 of any suitable derrick or hoist and a hoisting cable 30 attached to the hopper, as shown. The hopper 27 is substantially cylindrical in form and provided with a tight cover 31 which may be fastened down in any suitable manner. The hopper is large 75 80 enough to contain a charge of grout sufficient to fill one or more of the channels 25 and still provide an air space at the top. Communication is afforded to this air space through the pipe 32 to which is attached a 85 pressure hose 33. Any suitable means is provided for introducing compressed air through the pipe 32 into the top of the hopper so that grout will be forced therefrom through the barrel 28 under pressure. 90

Means are provided for shutting off the flow of grout from the hopper into the barrel when desired. Such means comprise a pair of gates 34 pivoted at 35, as shown. In Figure 5, these gates are shown in their 95 closed position in solid lines, and in their opened position in broken lines. The two gates are mounted on the transverse pivoted shafts 35 having on their front ends the intermeshing segmental gears 36. One of the shafts 35 carries on its end the arm 37 to which is attached the operating lever 38 provided with a detent 39 and quadrant 40. When the lever 38 is in the position shown in Figure 4 with the detent 39 engaged in the notch in the quadrant, the gates are closed. An operating cord 41 is provided so that when this cord is pulled it will move the operating lever 38 to the left (as viewed in Figure 4) to the position shown in Figure 4 to close the gates and stop the further discharge of grout. When the lever reaches 100 105 110

this position, the detent 39 forced by the spring 39^a engages the notch in the quadrant and thus holds the gates closed.

The upper end of the barrel of the gun 5 is provided with a funnel shaped, or flared member, 50 into which the lower end of the hopper fits. The spout 51 at the lower end of the hopper is beveled, as indicated at 52, in order to make a snug fit with the funnel 10 50 when it is forced down into the same. The following means are provided for holding the spout 51 snugly inside of the funnel 50. Mounted on the hopper a short distance above the gate mechanism is a circular ring 15 or shelf 55 adapted to be engaged by four hooks 56 which are pivoted to the upper edge of the funnel shaped member 50, as shown. Each of these hooks 56 is provided with a downwardly projecting arm 57 and a small 20 spring 58 operating to yieldingly hold the hooks in position in engagement with the ring 55. There is also provided a rotatable cam ring 59 held by suitable supporting means 60. This cam ring 59 is formed so 25 that when it is in the position shown in Figures 7 and 8, the hooks 56 will be in engagement with the shelf 55. The cam ring, however, may be rotated by means of the operating handle 59^a to cause its widened 30 parts to engage with the arms 57 to force them inwardly and thus disengage the hooks 56 from the ring 55 to permit the hopper to be withdrawn from the flared member 50.

A flexible connection is arranged at the 35 upper end of the barrel of the gun to permit the requisite twisting and bending movements between the hopper and the barrel. This flexible connection comprises, in general, a flexible hose or tube 60^a which may 40 be made of canvas, rubber, fabric, or other suitable material. The upper end of the flexible tube 60^a is clamped on to the lower end or spout 50^a of the funnel shaped member 50 by means of the clamp ring 61; and 45 its lower end is inserted in the upper end of the barrel 28. The upper end of the barrel 28 is provided with a clamp ring 62 similar to the ring 61, and these two rings are connected by six bars 63 having round 50 balls 64 at their ends. The rings 61 and 62 are provided with flanges 65 and 66, respectively. Each of these flanges has formed in it six hemispherically shaped sockets adapted 55 to accommodate the balls 64. The flanges 65 and 66 have bolted to them two rings 68 and 69, respectively, each having six hemispherically shaped recesses adapted to 60 coact with the recesses in the rings 65 and 66 to form sockets to accommodate the balls 64 on the rods 63. The recesses in the rings 68 and 69 are provided with radial slots to permit the insertion of the bars. The completed 65 spherical sockets are sufficiently larger than the balls 64 to permit free movement of the same therein, and each of the holes into the

recesses in the rings 68 and 69, through which the bars 63 pass are sufficiently large to permit twisting and movement of the same therein. By means of this construction, the bars 63 will take tensile and compression 70 strain between the hopper and the barrel of the gun and still permit sufficient twisting and bending movement between these members.

In the practice of my invention, the piles 75 20 are driven or placed in position as shown, to leave the channels 25 between. The hopper of the gun is then filled with concrete nearly to the top with the gates closed. The cap member 70 is then pressed into the 80 bottom of the barrel 28. The barrel of the gun is then lowered into one of the channels 25. The cap member 70 prevents any water or other material that might be in the channel from going up into the barrel of the 85 gun. The lowering of the barrel with this cap member on the end serves therefore to displace any water that there may be in the channel. It will be noted that the barrel has a cross sectional area substantially the 90 same as the cross section of the channel 25. In other words, the barrel substantially fills the channel. There is sufficient space, however, between the barrel and the channel to permit any water to escape that there 95 might be in the channel. Such water oozes up around the sides of the barrel as it is lowered or else escapes through the cracks 26. When the barrel reaches the bottom of the channel, compressed air is introduced 100 into the top of the hopper through the pipe 32 to the desired pressure, and the gates 34 at the bottom of the hopper are then opened, permitting the grout 72 to be discharged from the hopper through the barrel into 105 the channel. The pressure of the grout is sufficient to remove the cap member 70 from the end of the barrel. This member is preferably formed out of sheet metal and remains at the bottom of the channel; a new member 110 being provided for each channel. It is obvious that the air pressure and the weight of the column of grout causes the grout to issue from the mouth of the barrel with considerable pressure, so that the channel itself and the cracks, such as 26, around it, are completely filled with grout under pressure. As the grout issues from the mouth of the barrel, the barrel is withdrawn, the speed of withdrawal being timed so that the channel and cracks and crevices will be completely filled.

If desired, a reenforcing bar, such as indicated by 73, in Fig. 3, may be placed in the channel 25. When it is desired to use 125 such a reenforcing bar, I prefer to separate the barrel of the gun from the hopper and lower it into the channel 25 with its cap member 70. I then insert the reenforcing bar 73 into the barrel, and then join the hopper 130

onto the barrel by means of the hooks 56. The grout is then discharged in the usual manner to remove the cap 70 and fill the channel, the barrel being withdrawn as the 5 grout is discharged. The reenforcing member 73 remains in the channel surrounded by grout.

While I have shown and described certain 10 embodiments of my invention, it is to be understood that it is capable of many modifications. Changes, therefore, in the construction and arrangement may be made without departing from the spirit and scope of the 15 invention as disclosed in the appended claims, in which it is my intention to claim all novelty inherent in my invention as broadly as possible in view of the prior art.

What I claim as new and desire to secure by Letters Patent is:

20 1. A bonding apparatus adapted for grouting channels between sheet piles, comprising a barrel adapted to substantially fill one of said channels, a removable cap on the lower end of said barrel, means for raising 25 and lowering said barrel in one of said channels, and means for feeding cementitious material into said barrel at the top thereof to remove said cap.

2. A bonding apparatus adapted for 30 grouting channels between sheet piles, comprising a barrel adapted to substantially fill one of said channels, a removable cap on the lower end of said barrel, means for raising and lowering said barrel in one of said 35 channels, and means for feeding cementitious material under pressure into said barrel at the top thereof to remove said cap.

3. A bonding apparatus comprising a tubular barrel, a closed hopper attached to the

upper end of the barrel, a flexible joint between the hopper and the barrel, a confined air space at the upper part of the hopper, and means for introducing compressed air into said confined air space.

4. A bonding apparatus comprising a tubular barrel, a hopper attached to the upper end thereof, a flexible joint between said barrel and said hopper, and a gate at the bottom of the hopper adapted to control the flow of cementitious material from the hopper into the barrel.

5. A bonding apparatus comprising a tubular barrel, a removable cap at the lower end thereof, and means for feeding cementitious material under pressure into the upper end thereof.

6. A bonding apparatus comprising a tubular barrel, a removable cap at the lower end thereof, and a hopper adapted to contain cementitious material attached to the upper end of said barrel.

7. A bonding apparatus adapted for grouting channels between sheet piles, comprising a tubular barrel adapted to substantially fill one of said channels, means for raising and lowering said barrel in said channel, a hopper attached to the upper end of said barrel, a flexible joint between said barrel and said hopper, a gate at the bottom of the hopper adapted to control the flow of cementitious material from the hopper into the barrel, a confined air space at the upper part of the hopper, and means for introducing compressed air into said confined air space.

In witness whereof, I have hereunto set my hand and seal this 2 day of August 1923.

LYMAN B. LANGWORTHY. [L.s.]
